UNITED STATES PATENT OFFICE.

GEORGE MORSE GUILD, OF BOSTON, MASSACHUSETTS, ASSIGNOR TO H. E. GUILD, OF SAME PLACE.

UPRIGHT-PIANO ACTION.

SPECIFICATION forming part of Letters Patent No. 450,694, dated April 21, 1891.

Application filed March 7, 1890. Serial No. 343,030. (No model.)

To all whom it may concern:

Be it known that I, GEORGE MORSE GUILD, a citizen of the United States, residing at Boston, in the county of Suffolk and State 5 of Massachusetts, have invented certain new and useful Improvements in Upright-Piano Actions; and I do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 Figure 1 is a side elevation of an action for upright pianos provided with my improvements. Fig. 2 is an edge view of the jack. Fig. 3 is a view of the jack and its rocker, the flange-pieces *i* and *r*, the swing *I*, and a 20 portion of the rail *G*. Fig. 4 represents the hammer-butt as made without the stop *g*.

The object of my improvements is to provide an upright-piano action of such construction that it will be positive in its working and 25 that will be free from the many delicate and troublesome parts that are in the actions now in general use, which are continually getting out of order and are a source of annoyance and expense to keep in repair.

30 The nature of my invention is defined in the claims hereinafter presented.

In the drawings, *A* denotes the key, which is fulerumed at *a*.

B is the combined lifter and back-check, it 35 consisting of an upright bar provided in its lower end with an adjusting-screw *C*, the head of which bears on leather or a cushion *b*, applied to the key, said head provided with holes to receive a rod or implement by which the 40 screw can be turned, or a portion of the head of said screw may be prismatic, if preferred, so that it can be operated by a wrench, as may be desired, to adjust the lifter in altitude to take up the space caused by the packing of 45 the leather or cloth *b*. The said lifter or bar has a projection *c* near its top, which extends over the hammer-butt, as shown, and on the descent of the lifter operates to swing the hammer back against its rail if for any reason 50 it should fail of its own accord to return to said rail, and said bar on the edge of it toward

the hammer is supplied with leather or a cushion *c'*, which serves as a back-check to operate with the adjacent curved leathered portion *d* of the hammer-butt to catch and 55 hold the hammer *E* after it has struck the string and prevent its rebound, and also hold said hammer near to the string in position to quickly repeat the blow when it is desired. The said hammer-butt is notched at *e* and provided with a bearing *f* and a stop *g* for the upper end of the jack, and it is also weighted at *u*. The hammer is pivoted at *v* to one end of the flange-piece *w*, and the damper-lever *R* is fulerumed at *g'* to the other end of said 65 flange-piece, the latter being secured to the rail *S*.

T is the damper-head, and *U* represents the string.

F is the jack-rocker, one end being pivoted 70 at *h* to the flange-piece *i*, the latter fixed by two screws to the rail *G*, and the other end of the rocker *F* is pivoted at *j* to the lifter *B*.

H is the jack, provided with three arms and pivoted to the said rocker at *k* and extending 75 below the same, as shown, a spring *l* being arranged to bear at its free end against the lower arm *m* of said jack. Said spring fixed to the lifter, as represented, keeps the upper end of the jack against the stop *g* of the hammer-butt. The said arm *m* of the jack is slotted 80 at *m'* to receive the jack-rocker. A regulating-button *n*, whose screw *n'* extends through the lifter, operates when in upward movement the upper end of the jack with relation to surface *f* of the hammer-butt, and the arm *o* of the jack operates with a regulating-button *p* to throw at the proper time the top end of the jack into the said notch *e* to relieve the hammer from said jack. 85

I is the swing, pivoted to the lifter at *q* and to the flange-piece *r* at *s*, said swing having the arm *t* to operate the damper. A spring *z*, fixed to the rail *G*, bears downward on said swing *I*, and the latter projects beyond the 95 lifter *B* at *x* to operate with a rail *V* to limit the upward movement of said lifter when raised by the key. The rail *G* is provided with beads or ridges *a'* and *b'*, against which the flange-pieces *i* and *r* are borne, respectively, by the screws which confine said pieces to the rail. Such arrangement, besides confin- 100

ing the said pieces to the rail more securely than can be done by a single screw, also admits of a change of position of the pivots *h* and *s* to effect the adjustment of the back-
5 check *c'* to the curved portion *d* of the hammer-butt.

The jack-rocker *F* and the swing *I*, I usually make of brass or other suitable plate metal, in which the pivot-pins *h*, *k*, and *j* of the rocker and *s* and *q* of the swing are driven so tightly that they cannot move or work loose therein. This construction of the rocker and swing overcomes a serious objection in upright-piano actions, as when said rocker 15 and swing are made of wood, owing to the shrinkage of the same, it is difficult to so apply the said pins to them that the pins will remain fixed therein. Consequently said pivot-pins, particularly those bearing in the lifter 20 and jack, often work loose and project beyond the surface of said parts, and when the action is in operation they will cut into the next adjacent parts and materially injure them, and also interfere with the working of the action. 25 Defects of this kind in upright pianos are exceedingly troublesome and of every-day occurrence and are expensive and difficult ones to repair. Furthermore, by making said rocker and swing of metal they can be made much thinner than when made of wood, which admits 30 of longer bearings in the flange-pieces *i* and *r* and in the jack and the lifter for the journals of said pins. Hence it will be seen that by this change in construction said parts will be 35 supported to better advantage, will keep in place better, and are not liable to get out of order. Besides, by having longer bearings in the flange-pieces for the pins the cloth or leather bushings in said bearings can be confined therein, so that they will not be liable 40 to work loose, as they frequently do under the old construction, for the reason that they are so short.

In the action hereinbefore described the 45 operative parts are more substantial and of simpler construction than in the action now in general use in upright pianos, and, furthermore, my action is positive in operation, as no part of it can fail to do its work, and 50 is not liable to be affected by heat, cold, or dampness.

As will be perceived, the lifter *B* is made in one piece, extends above the heel of the hammer, and is provided with leather or a 55 cushion *c'*, which, with its support, answers as the back-check to the hammer, the heel of the said hammer operating directly against said back-check, which, owing to its construction, cannot spring or fail to perform its function, as the back-check often does when composed of a cushioned head and a wire supported by the jack-rocker, as heretofore. Furthermore, said lifter is provided with means of 60 vertical and lateral adjustment, as represented, to take up wear of parts. Furthermore, it will be seen that the jack, instead of being pivoted to a flange-piece secured to and pro-

jecting above the jack-rocker, as heretofore, is in my action pivoted directly to said rocker and has an arm extending below it, against 70 which a spring bears, which is stiff enough to be reliable to keep the top of the jack in its proper position with relation to the hammer-butt. In the action now in general use in upright pianos the jack is kept in position by a spiral spring of very delicate construction, which requires the nicest adjustment or the jack will not do its work, and because said spring is so frail it is constantly getting out of order and is a source of much 80 care and requires frequent readjustment. Moreover, the said jack must be kept in exact position against the hammer-butt, and the latter must be covered accurately and be perfect in shape or the jack will not perform its function when the key is struck, but will slip away from the said butt and fail to operate the hammer sufficiently to strike the string. A little dampness will prevent its 85 working at all, and it is a constant source of annoyance. By my improvements this delicacy and nicety of construction of the parts above mentioned is avoided, and the jack as improved by me cannot fail to cause the hammer when the key is struck to strike the 90 string. It will be observed that the top of the jack *H* when operating the hammer moves toward the pivot of the hammer instead of away from it, as in the action now in use. On striking the key the lifter *B* and parts 100 connected to it and also the jack will rise (said movement being limited by the stop *x* and rail *V*) and the upper part of the jack will be kept against the stop *g* of the hammer-butt by the spring *l* until the button *n* 105 is borne against the jack and moves it along the surface *f* of the butt till the point 1 of the jack reaches the point 2 of the butt. Then the arm *o* of the jack will strike the button *p* and instantly move the top of the 110 jack into the notch *e* of the butt and leave the hammer free to return to the hammer-rest *W* the moment the key is released from pressure. If the key is struck suddenly and 115 not held at all by the performer, the hammer will strike the string and return instantly to the rest *W*, the projection *c* preventing any rebound of the hammer. Furthermore, when 120 the key is struck and held down by the performer, the back-check *c'* operates with the curved portion *d* of the butt to stop the return movement of the hammer instantly after it has struck the string and holds said hammer near to said string ready for repeating the blow, which requires but a slight movement of the key.

From the foregoing it will be seen that by my improvements the jack cannot slip away from under the hammer-butt or fail to cause the hammer to strike the string when the key is struck, and, furthermore, the action is much simpler in construction, as I dispense with many troublesome parts that are in the old action—viz., the regulating-rail and the braces

fixed to the center rail that support said regulating-rail, the hammer-spring rail and hammer-spring, the bridle-wire and bridle-tape, the back-stop and back-stop shank secured to the hammer-butt, the jack-flange, the back-check, and the back-check wire supported by the jack-rocker. Furthermore, the butt of the hammer may be formed without the stop or projection *g*, as shown in Fig. 4, in which case the top of the jack will be kept in its due relation to the surface *f* of the butt by the regulating-button *n*.

I make no claim to any portion of a piano-action constructed of doubled-up sheet metal, as shown and described in United States patent to Roedern, No. 213,940, dated April 1, 1879.

What I claim is—

1. In an upright-piano action, the lifter *B*, pivoted to the jack-rocker and to the swing extending above the hammer-butt and provided with the projection *c* and back-check *c'*, as and for the purpose explained.

2. In an upright-piano action, the hammer having its butt provided with the curved portion or back-stop *d*, jack-stop *g*, jack-bearing *f*, and relief-notch *e*, said notch being located between the jack-bearing and the pivot of the hammer, as and for the purpose described.

3. In an upright-piano action, the rail *G*, formed with the beads *a' b'*, combined with the flange-pieces *i* and *r*, and the screws supporting each of said pieces with relation to said beads, as and for the purpose set forth.

4. In an upright-piano action, the hammer having its butt provided with the back-stop *d*, the jack-stop *g*, jack-bearing *f*, and the relief-notch *e*, the latter being located between the jack-bearing and the pivot of the hammer, in combination with the tri-armed jack having a slotted arm, the jack-rocker, and the lifter *B*, all arranged and supported essentially as represented.

5. In an upright-piano action, the jack provided with three arms, the lower arm slotted at *m'* to receive the jack-rocker, as represented.

6. In an upright-piano action, the combination of the jack provided with three arms and the slot *m'* with the jack-rocker arranged in said slot and pivoted to the jack, as represented.

7. In an upright-piano action, the combined lifter and back-check slotted to receive the

jack-rocker and swing and provided with the adjusting-screw *C*, the latter adapted to work in the lower part of and lengthwise in said lifter, as and for the purpose explained.

8. An upright-piano action consisting of the lifter *B*, provided with the projection *c*, back-check *c'*, the adjusting-screw *C*, the regulating-button *n*, and spring *l*, the hammer having its butt provided with the curved portion or back-stop *d*, the projection *g*, jack-bearing *f*, notch *e*, and weight *u*, the flange-piece *w*, the damper and spring *y*, regulating-button *p*, the tri-armed jack, slotted as explained, the jack-rocker, the flange-pieces *i* and *r*, sustained as explained, the swing provided with arm *t*, and the spring *z*, all arranged, supported, and to operate essentially as described.

9. In an upright-piano action, the lifter *B*, pivoted to the jack-rocker and to the swing extending to or above the top of the hammer-butt and provided with the back-check *c'*, as and for the purpose set forth.

10. In an upright-piano action, the hammer having its butt formed with the curved portion or back-stop *d*, the jack-bearing *f*, and relief-notch *e*, said notch being located between the jack-bearing and the pivot of the hammer, as and for the purpose explained.

11. In an upright-piano action, the jack provided with three arms, the lower arm slotted to receive the jack-rocker, said jack when operated to release the hammer having its top moved toward the pivot of the hammer, as explained.

12. An upright-piano action consisting of the lifter *B*, provided with the projection *c*, back-check *c'*, the adjusting-screw *C*, the regulating-button *n*, and spring *l*, the hammer having its butt provided with the curved portion or back-stop *d*, the projection *g*, jack-bearing *f*, notch *e*, and weight *u*, the flange-piece *w*, the damper and spring *y*, regulating-button *p*, the tri-armed jack, slotted as explained, the jack-rocker, the flange-pieces *i* and *r*, sustained as explained, and the swing provided with arm *t*, all arranged, supported, and to operate essentially as described.

In testimony whereof I affix my signature in presence of two witnesses.

GEORGE MORSE GUILD.
